UNITED STATES PATENT OFFICE.

CHARLES HOSEK, OF FLORESVILLE, TEXAS.

LIQUID-FUEL BURNER.

1,392,012.

Specification of Letters Patent. Patented Sept. 27, 1921.

Application filed January 15, 1921. Serial No. 437,506.

To all whom it may concern:

Be it known that I, CHARLES HOSEK, a citizen of the United States, residing at Floresville, in the county of Wilson and State of Texas, have invented certain new and useful Improvements in Liquid-Fuel Burners, of which the following is a specification.

This invention relates to certain new and useful improvements in liquid fuel burners, and the same has particular reference to improvements of that type of burner in which kerosene may be practically employed as fuel, and which may be employed for 10 efficiently heating barns or the like.

The principal object of the invention is to provide a burner of this kind which may be utilized where an intense flame is needed, and which is of such construction as to be 20 cheaply and easily manufactured as well as readily placed into effective use.

Broadly, the invention resides in the provision of a supply pipe extending downwardly and then formed in upwardly progressing coils terminating in an upstanding end having an inverted U-shaped pipe member secured thereon so that the outlet end of the latter pipe member projects downwardly toward the coils about centrally of the space 25 inclosed by the latter, whereby when the fuel is ignited at the outlet end of said U-shaped member, the flame is directed toward the coils so as to heat the latter and vaporize the fuel in its passage through the coils to 30 the burner tip.

Referring to the drawing, the figure is one showing the supply pipe partly broken away with the coils in side elevation and with the U-shaped member and burner tip 40 in longitudinal section.

Referring more in detail to the drawing, the invention contemplates the provision of a liquid fuel burner including a supply pipe 5 which may extend from any desired 45 point where the storage tank for the fuel is located. This supply pipe extends downwardly as shown and it is then directed laterally as at 6 where it is formed into a plurality of closely related coils 7 arranged in helical formation and progressing upwardly. The pipe then extends from the top of the coils in a vertical direction as at 8 where it terminates in a screw threaded end 9 with a flange 10 at the base of the threads. An

inverted U-shaped pipe member 11 has one 55 end threaded onto the threaded portion 9 of the pipe end 8 so that the lower end of said U-shaped pipe abuts the flange 10 when the intermediate portion of the U-shaped pipe extends radially inwardly of the coils with 60 the free end of the U-shaped pipe 11 directed downwardly toward the coils at about the center of the space bounded by said coils. The free end of the U-shaped pipe 11 terminates a slight distance above the uppermost 65 coil and it is internally threaded for detachable reception of the male nipple 12 provided on the tapered burner tip 13. The burner tip 13 and the adjacent end of the pipe 11 both have flanges 14 and 15 respectively 70 which abut each other when the burner is properly secured in place, and said burner is provided with a central outlet port 16 as well as oblique side outlet ports 17 adjacent the central port 16. In this way the flame 75 is dispersed in numerous directions to impinge upon the coils for heating the same to the desired degree.

It will thus be seen that as the fuel issues from the burner, the same may be ignited 80 and the heat from this flame is utilized to heat the fuel in the coils 7 preliminary to the ignition of the fuel at the burner tip.

It is believed that the construction and operation as well as the advantages of the 85 present invention will be readily understood from the foregoing description by those skilled in the art.

Minor changes may be made without departing from the spirit and scope of the invention as claimed.

What is claimed as new is:

A liquid fuel burner of the class described including a fuel supply pipe extending downwardly and then laterally where it is 95 formed into a series of closely related upwardly progressing helical coils, a supply pipe terminating at the uppermost coil adjacent one side of the burner and then extending upwardly and having an annular 100 flange adjacent its upper end, the portion of the pipe above the flange being threaded, an inverted substantially U-shaped pipe having one end threaded upon said threaded end of the supply pipe, the said pipe being arranged with its central portion extending radially inwardly toward the center of the coils above the latter and with its free

end directed downwardly toward the coils and terminating slightly above the latter and provided with an outwardly extending annular flange and a burner tip secured in 5 the free end of said inverted U-shaped pipe above the uppermost coil and having ports to direct the flames laterally and down-

wardly for effectively heating said coils and provided with a flange intermediate its ends for impinging against the said flange of the 10 U-shaped pipe.

In testimony whereof I affix my signature.

CHARLES HOSÉK.
